CLAIM

The ornamental design for an absorbent article with releasable backsheet material, as shown and described.

DESCRIPTION

FIG. 1 is a top plan view of an absorbent article with releasable backsheet material; and,

FIG. 2 is a bottom plan view of an absorbent article with releasable backsheet material.

The broken lines immediately adjacent the shaded areas represent the bounds of the claim and all other broken lines are for illustrative purposes only. None of the broken lines form a part of the claimed design.
